EDWARD J. O'CONNELL, OF FORT WAYNE, INDIANA, ASSIGNOR TO DEISTER
CONCENTRATOR COMPANY, A CORPORATION OF INDIANA.

FEEDING APPLIANCE FOR ORE-CONCENTRATORS.

1,245,611.

Specification of Letters Patent. Patented Nov. 6, 1917.

Application filed April 13, 1916. Serial No. 90,801.

To all whom it may concern:

Be it known that I, EDWARD J. O'CONNELL, a citizen of the United States of America, and resident of Fort Wayne, in the county of Allen and State of Indiana, have invented certain new and useful Improvements in Feeding Appliances for Ore-Concentrators, of which the following is a specification.

10 This invention relates to improvements in feeding appliances for ore concentrators of the reciprocating-table type, and the object of the improvement is to effect a broader distribution of the pulp as it is applied to the concentrating surface of the table than in ordinary practice; and a further object is to utilize that portion of the pulp which enters the feed-box, that contains the finer particles of solids, as a dressing agent for 15 treating the settled solids that form in a mass across the surface of the table, thereby facilitating the saving of fine values that are contained in the thinner portion of the pulp. It is also an object to apply the dressing- 20 water in the manner hereinafter disclosed which effects a blending of the pulp and dressing-water.

The objects of the invention are accomplished by the construction illustrated in the 25 accompanying drawings in which:

Figure 1 is a plan view of a concentrating table showing the invention applied thereto;

Fig. 2 is a side elevation of the feed-box and dressing-water launder;

30 Fig. 3 is a cross-section of Fig. 2 on the line $x-x$ thereof;

Fig. 4 is a cross-section of Fig. 2 on the line $y-y$ thereof; and

Fig. 5 is a cross-section of Fig. 2 on the 40 line $z-z$ thereof.

Similar characters of reference indicate corresponding parts throughout the several views and referring now to the same:

1 is a reciprocating concentrating table of 45 a well known type, (2) is a feed-box mounted in connection with the table in the usual relation therewith, and (3) is a dressing-water launder that is arranged in connection with the table and in conjunction with the 50 feed-box.

The feed-box is secured to the table in the ordinary manner and has a series of feed apertures (4) adjacent its bottom extending through its side-wall (5) which is positioned along the splash-board (6) at the

feed side of the table. The feed-box has an extension (7) at its forward end, the bottom of which is a continuation of the bottom proper of the feed-box, the side walls (5) and (5'), however, are of less height than 60 the major portion thereof.

The dressing-water launder (3) is situated so that its rear portion overlaps the extension of the feed-box and is adapted to discharge its contents of water through its 65 various discharge openings (8) made in its side adjacent the splash-board (6) and which extend from one end of the box to the other including that portion thereof that overlaps the extension of the pulp feed-box. 70

The action of the table is reciprocal, and is produced in the customary manner, and also the slant of the table, both laterally and longitudinally is in accordance with the customary practice. Ripples (not shown) also 75 may be superimposed upon the table as desired, the intention being that the gravitational flow of the mass of solids that settle upon the surface of the table will pass, as discharged from the feed-box, across the surface of the table diagonally toward the juncture of the concentrates discharge end (9) and the tailings discharge side (10) thereof, approximately along the dotted line (X') appearing on Fig. 1. The ore pulp is 80 introduced into the feed-box at the rear portion thereof as indicated by (12), and flows forwardly throughout the length of the box. The coarser solids, as they tend to settle in the box drift toward the wall 85 (5), owing to the slant of the bottom of the box, and pass through the openings (4) onto the adjacent surface of the table. The solids thus discharged from the feed-box form in a mass and flow diagonally across the table 90 approximately along the line (X'). The movement of the mass is influenced by both gravitation which force is toward the tailings discharge side (10), and by the impelling action of the table that tends to move 100 the mass toward the concentrates discharge end (9). The thinner portion of the pulp that contains the very fine solids flows forwardly in the feed-box over the coarser solids and becomes discharged from the extension (7) onto the surface of the deck 105 ahead of the transient mass of coarse solids. The thin pulp mingled with the dressing-water that is introduced onto the table in conjunction therewith flows gravitally across 110

the table, washing in its passage the mass of solids. The very fine mineral particles in the thin pulp that flows with the dressing-water tend to mingle with the coarser values 5 moving on the surface of the table and pass therewith to the concentrates discharge end where they are recovered with the general mass of separated metal.

By this construction a material portion of 10 the necessary washing of the mass of solids is effected by the use of the fluid containing values that are recovered therefrom in the washing process, and which values, together with the coarser values become cleansed 15 with the intermingling dressing-water.

What I claim is:—

1. In combination with a reciprocating concentrating table, a feed-box having a forward extension, and a series of discharge 20 openings in one of its walls extending throughout its length including the extension, and a dressing-water launder having a series of discharge openings in one of its side walls extending throughout its length, 25 the rear portion of the launder being positioned so as to overlap the said extension of the feed-box.
2. In combination with a reciprocating, concentrating table, a feed-box adapted to 30 distribute pulp upon the table, and a dress-

ing-water launder adapted to distribute dressing-water thereon, said launder being positioned so as to overlap the forward part of the feed-box.

3. In combination with a reciprocating, 35 concentrating table, a feed-box adapted to discharge pulp throughout its length upon the adjacent surface of the table, and a dressing-water launder overlapping the forward part of the feed-box and adapted for 40 the discharge of dressing-water therefrom throughout its length upon the table.

4. In combination with a reciprocating, concentrating table, a feed-box for distributing pulp upon the table at the feed side 45 thereof and having an extension for conveying to and distributing the thinner portion of the pulp upon that surface of the table ahead of the coarse, and a dressing-water launder positioned so as to discharge dressing-water in portions, with the thinner pulp 50 as it passes from the extension of the feed-box and ahead of the pulp.

In testimony whereof I affix my signature in presence of two witnesses.

EDWARD J. O'CONNELL.
